(57) **CLAIM**

The ornamental design for a MILITARY HEARSE, as shown and described.

DESCRIPTION

FIG. 1 is a right side elevation view of a MILITARY HEARSE showing my new design;
FIG. 2 is a rear elevation view of the MILITARY HEARSE;
FIG. 3 is a rear elevation view of the MILITARY HEARSE;
FIG. 4 is a top plan of the MILITARY HEARSE;
FIG. 5 is a right side elevation view of the MILITARY HEARSE according to the first embodiment;
FIG. 6 is a rear elevation view of the MILITARY HEARSE with the rear hatch open;
FIG. 7 is a rear perspective view of the MILITARY HEARSE with the rear hatch open;
FIG. 8 is another rear perspective view of the MILITARY HEARSE with the rear hatch open; and
FIG. 9 is a rear left side perspective view of the MILITARY HEARSE.

The broken line shown in the drawings are for the purpose of illustrating portions of the article and form no part of the claimed design.
